UNITED STATES PATENT OFFICE

CORNELIS BOL, OF EINDHOVEN, NETHERLANDS, ASSIGNOR TO RADIO CORPORATION OF AMERICA, A CORPORATION OF DELAWARE

INDUCTANCE COIL

Application filed February 1, 1930, Serial No. 425,095, and in the Netherlands March 2, 1929.

The present invention relates to coils, and more particularly to improvements in, or relating to, inductance coils for radio sets.

In constructing radio sets it is desirable that inductance coils be available, and that the external field of the coils be as feeble as possible. Thus, a compact construction is assured in which no undue couplings occur. For this purpose the so-called toroid coils are frequently used. These toroid coils have a limitation in that they differ among themselves to a fairly marked extent as regards the value of the inductance, so that when mounting a number of equal coils in a set it is not possible to take the required number at will from among a great number of coils, but a certain selection must be made, it being necessary to select sets of coils having matched values. This is especially important if it is desired to operate a great number of tuned circuits by means of one controlling device, as for example by arranging the rotors of a gang of condensers on a common shaft operated by a single control. Toroid coils have the additional disadvantage of being mechanically weak since the practice is to mount these coils without a core, and by accidental contacts, which obviously can never be avoided entirely, the inductance may become materially modified.

This invention provides a means for making the coils of the same type, so that all of them possess the same inductance, and also retain it. For this purpose the coils are mounted in a screening case or shield, preferably of metal having a low ohmic resistance, as for example, copper. Thus a coil is obtained which is mechanically protected, and the inductance of which does not become modified by an accidental contact. Since it is practically impossible to make a great number of coils having absolutely the same inductance, the coil may be arranged in the screening case, in such manner that after the closing lid has been placed in position, the box and lid have no longer between them interstices that give passage to a field, and the inductance can be varied from without the case.

This may, for example, be effected by mov-

ably arranging the coil itself, or an auxiliary member, in the case. Once the proper position is ascertained, this position is fixed. The proper position of the adjustable member may be ascertained, for example, by inserting the coils of a series, after they have been arranged in the screening case, one at a time into a permanent measuring installation, and varying the position until the indicating instrument of the measuring installation takes the proper position. The adjusting members or the coil itself are then set tightly in this position. Alternatively, the coil may be arranged in the case at once so as to be stationary and the inductance may be varied by changing the walls in form. Instead of an ordinary box an enclosure consisting of two parts telescoping one within the other may serve as the case.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several organizations whereby my invention may be carried into effect.

The invention will be more clearly understood by reference to the accompanying drawing in which an embodiment is illustrated.

In the said drawing,

Fig. 1 is a section of a screening case with an elevation of the enclosed coil,

Fig. 2 is a plan elevation view of the screening case, shown in Fig. 1 with the strip 8 omitted,

Fig. 3 is a view similar to Fig. 1, but showing a modification,

Fig. 4 illustrates a view similar to Fig. 1, but showing a screening case having great resistance to deformation,

Fig. 5 shows a packing gland around the terminal wire of the coil enclosed in the case, of Fig. 4.

Fig. 6 shows a sectional view of still another modification.

Referring to Fig. 1, 1 designates the screen-

100

- ing case which may be of metal. The wall must be thick enough to prevent any mechanical deformation. In addition, the case preferably should be hermetically closed in order to ensure optimum screening. 2 designates the cylinder or core on which the coil is wound. The ends of the coil extend outwardly through tubes 4 and 5 secured to the case. 8 and 9 designate metal strips which extend outwardly through slit-shaped apertures 6 and 7 respectively in the case 1. The case is entirely closed with the exception of the apertures 6 and 7 and the orifices of the tubes 4 and 5 so that the end walls have throughout a good metallic contact with the cylindrical wall. When the coil is disposed within the case, as shown in Fig. 1, the coil is then connected to a measuring device and by means of the strips 8 and 9 the coil is shifted until the proper value of the inductance is attained. In this position the strips 8 and 9 are soldered to the walls of the case so that the apertures 6 and 7 are entirely closed. 25 If desired, one of the ends of the coil may be grounded to one of the strips 8 or 9 or directly to the case itself and one of the tubes 4 or 5 and the adjacent opening in the case may then be dispensed with. 30 To obtain more perfect screening the ends of the coil are led out through the tubes 4 and 5 but in some instances these tubes can be dispensed with. The ends of the coil are preferably led out at points at which the field of the coil tends as little as possible to emerge, for example where the lines of force tend to pass parallel to the wall of the case as in the planes of the coils as shown in Fig. 1. 40 Fig. 3 shows a different construction in which the coil is entirely mounted in a permanent and stationary manner in the case and the inductance is adjusted, by shifting by means of an adjusting screw 10, a metal strip 12 secured to the lid or other part of the case. In this case the coil is mounted on the case bottom by means of legs 13 attached both to the core of the coil and to the case. 50 Fig. 4 shows a screening case the end walls of which are spherical. This has the advantage that the mechanical resistance to change in form is greater than in the case of flat end walls. 55 The screening case shown in Fig. 4 is entirely closed and only the ends of the coil are led out. The desired adjustment of the inductance is obtained by deformation, as for example by forcing in one of the end walls, or otherwise changing its form. The core or other support of the coil is secured to one of the end walls by means of two straps 14. The straps are preferably secured at points which do not shift when the wall is changed in form to adjust the inductance. This may be as- sured by soldering the straps to the end wall close to the border. 60 In this case the inductance may be adjusted in a very simple manner by placing the case in a bench vise, connecting the coil in the stationary measuring device and adjusting the vise until the meter shows the proper value of inductance. The measuring device may, for example, be an arrangement comprising a tuned circuit the inductance of which is constituted wholly or partly by that of the coil to be measured. The tuning is effected by varying the inductance. This method can be carried out very rapidly and gives very reliable results. The arrangement shown in Fig. 4 has the advantage that, after adjustment no soldering or other manipulation of the coil is required. The end caps will hold their deformed shape when the pressure of the vise is removed. 65 Instead of convex the end walls may be concave in order to ensure resistance to change in form. The screening case may be such that one of the walls is little resilient and does not spring back after being forced in. 70 An additional advantage of concave or convex end walls consists in that the cases can be exhausted without any change in form being produced as the barometric pressure varies. 75 In this case the apertures through which the ends of the coil are taken outwards must be hermetically closed. This may be effected, for example, in the manner shown in Fig. 5. 1 is the wall of the screening case which has secured to it, for example by soldering, an inside cylindrical member 18 and an outside sleeve 16. 15 designates a small sleeve or tube of insulating material through which the wire 17 extends. The small cup formed by 16 is filled with some suitable cementing material 19. 80 In order to ascertain whether the case is hermetically closed it may have mounted on it a conventional cylindrical valve member 20 adapted to be joined to the elastic tube of an air pump. 85 The screening cases may be exhausted and then filled with dry air. Thus one can avoid water vapour which otherwise might be present within the case and be precipitated on a decrease in temperature. In this case the shield or screen must likewise be hermetically closed. 90 If the case consists of two parts 21 and 22 telescoping one within the other, as shown in Fig. 6, provision should be made for the walls of the parts that slide one within the other overlapping each other in order to prevent the field of the coil from emerging. In this case the inductance may be corrected by more or less slipping the parts one within the other. 95 100 105 110 115 120 125 130

As a rule only such a thin layer of metal is required for the electric screening that the mechanical protection would not be ensured thereby. In order to ensure the necessary mechanical strength the metal may be thicker than is required for the electric screening, but as an alternative the case may consist of insulating material and internally coated with metal. Alternatively, the case may be 10 of metal such as iron and internally coated with a thin layer of very good conducting metal, for example silver.

The described method of mounting the coils has the great advantage that coils are obtained having practically equal inductance, occupying very little space and being adapted to be arranged in close proximity to each other without there being any risk of undue magnetic or electrostatic coupling.

20 In order to make the entire set as compact as possible the switches may be mounted on the screening cases, which ensures the advantage of very short connections. The connections to the condensers may likewise be very short.

While I have indicated and described several systems for carrying my invention into effect, it will be apparent to one skilled in the art that my invention is, by no means 30 limited to the particular organizations shown and described, but that many modifications in the arrangements, as well as in the apparatus employed, may be made without departing from the scope of my invention as 35 set forth in the appended claims.

What I claim is:

1. A method of producing a shielded inductance coil which consists in disposing an inductance coil within a shielding container, 40 adjusting the spatial relationship between the said container and said coil to adjust the value of the coil inductance to a desired quantity, and evacuating the container.

2. A method of producing a shielded inductance coil which consists in disposing an inductance coil within a metallic, shielding container, adjusting the spatial relationship between the walls of said container and said coil to adjust the value of the coil inductance to a predetermined quantity, evacuating 50 the container, and filling the interior of the latter with dry air.

3. A method of producing a shielded inductance coil which consists in disposing an inductance coil within a shielding container, and bodily displacing the coil relative to the container walls to adjust the value of the coil inductance to a predetermined quantity.

60 4. A method of producing a shielded inductance coil which consists in disposing an inductance coil within a shielding container, varying the spatial relationship between at least one of the walls and the coil to adjust 65 the value of the coil inductance to a prede-

termined quantity, and evacuating the container.

5. A method of producing a shielded inductance coil which consists in disposing an inductance coil within a metallic, shielding container, affixing the coil to at least one of the walls of the container, varying the spatial relationship between at least one of the walls and the coil by deforming said wall to adjust the value of the coil inductance to a predetermined quantity, and exhausting the container.

6. A method of producing a shielded inductance coil which consists in disposing an inductance coil within a shielding container provided with terminal outlets, extending the terminals of the coil through said outlets, and bodily moving the coil relative to all the walls of the container to adjust the value of the coil inductance to a predetermined quantity.

7. In combination, a metallic, shielding container provided with a pair of openings, an inductance coil disposed within the interior of the container and having its terminals extending through the said openings, and means including a movable support for the coil for displacing the coil within the container to a desired position.
